H. AUBURN

LOOSE LEAF BINDER

Filed March 26, 1925

Inventor
HUBERT AUBURN

By Murray and Bugeller

Attorneys

UNITED STATES PATENT OFFICE.

HUBERT AUBURN, OF CINCINNATI, OHIO.

LOOSE-LEAF BINDER.

Application filed March 26, 1925. Serial No. 18,586.

To all whom it may concern:

Be it known that I, HUBERT AUBURN, a citizen of the United States of America, and a resident of Cincinnati, in the county 5 of Hamilton and State of Ohio, have invented new and useful Improvements in a Loose-Leaf Binder, of which the following is a specification.

My invention relates to hinge structures 10 of the type employed with loose leaf binders and the like.

An object of my invention is to improve the structure disclosed in my co-pending application, Serial No. 716,782.

Another object of my invention is to provide a hinge pin that cannot be inadvertently disassociated from the hinge member.

Another object of my invention is to provide a device that is simple and economical 20 of construction and operation, for performing the above objects.

These and other objects are attained by the means described herein and disclosed in the accompanying drawings, in which:

Fig. 1 is a perspective view of a loose leaf binder having embodied therein the hinge structure of my invention.

Fig. 2 is a sectional view taken on line 2-2 of Fig. 1.

Fig. 3 is a sectional view taken on line 3-3 of Fig. 2.

Fig. 4 is a perspective view of my improved hinge pin.

The loose leaf binder 10 may be of any 35 approved type, such as a key to lock and unlock the members, or any other desired type. The loose leaf binder disclosed in the drawings consists of oval shaped tubular members 11 and 12. The lower binder

40 members 11 has mounted on its posts 13 which extend upward through perforations 14 formed in the upper binder member 12. The upper binder member 12 contains in it a locking and unlocking device. Plugs 15

45 having a body 16 and a flange 17 are provided for sealing the ends of the binder members. Flange 17 abuts the edges of the binder members 11 and 12. A recess or notch 18 is provided in each of the plugs 15

50 for receiving one arm 19 of a U-shaped hinge pin 20. The notch extends the length of the body 16 and into the flange 17. The other arm 21 of the hinge pin 20 is received in a tubular extension or bore 22 carried by hinge plates 23 and 24. The

55 bore 22 is formed by turning the ends of

the plates 23 and 24 upon themselves and may extend the entire length of the plate, as shown in the drawings, or may be cut to the length of arm 21 of the hinge pin 20. 60 Covers 25 and 26 are secured to plates 23 and 24 by any suitable means, such as by rivets 27 passing through said covers 25 and 26 and plates 23 and 24.

The tubular housings 11 and 12 have 65 formed in them perforations 28 in which are received ends 29 of the arms 19 of the hinge pins 20. The end 29 of each arm 19 is bent at right angles to the body of said arms whereby an anchor or hook 30 is 70 formed. This anchor or hook 30 prevents the hinge pins 20 from becoming inadvertently separated from the binder members 11 and 12. As will be observed from Fig. 2 it will be necessary to move hinge pins 20 75 toward the center of the binder members 11 and 12 in order to remove said hinge pin 20 from the binder members and hinge plates 23 and 24. After hinge pins 20 are mounted in place end plugs 15 are positioned in the 80 ends of the housings 11 and 12. The plugs 15 are frictionally retained in position by indenting the housings 11 and 12 as shown at 31. It has been found in practice that to make the plugs of aluminum is very 85 satisfactory. It should be observed from Fig. 2 that the plugs 15 prevent the lateral displacement of the pins 18 while the hook 30 and shoulder 32, formed in the flange 17 of plugs 15, prevent longitudinal displacement 90 thereof, after the binder has been assembled. Should the plug 15 be inadvertently withdrawn from the housings 11 and 12 the hook 30 will retain the pin in place until the plug 95 is reinserted in the housing.

Although I have shown and described but one method of utilizing my invention, it will be readily apparent to those skilled in the art, that with a few modifications this device can be adapted to other uses within 100 the scope of this invention. The tubular housings 11 or 12 may be considered as one hinge member, and the plates 23 or 24 as the complementary hinge member. It is therefore obvious that this device can be 105 adapted to other uses than for loose leaf binders.

It should be observed from Figs. 2 and 4 that the end 29 of arm 19 has a point 33 formed on it. The tubular binder members 11 and 12 are covered with a fabric or leather which extends into the bore, and fre-

quently covers the perforation 28 thereby restricting the entrance into the said perforation 28. This makes it difficult to insert the hoop 30 into the perforation. The 5 point 33 cuts the fabric or leather thereby permitting the hook to enter said perforation 28.

What I claim is:

1. In a device of the class described the 10 combination of a tubular housing having a perforation therein, a hinge plate having a bore along its one edge adjacent the housing, a U-shaped hinge pin having a hook formed at the end of one arm, the said arm 15 being received in the housing and the hook being received in the perforation in the housing, the other arm being received in the bore in the hinge plate, a plug received and frictionally held in the tubular housing, the plug and hook preventing lateral 20 and longitudinal displacement of the hinge pin.
2. In a device of the class described the 25 combination of a tubular housing having a perforation therein, a hinge plate having a

bore along its one edge, a U-shaped hinge pin, one arm of the hinge pin having a hook formed at the end thereof, and received in the housing and perforation, the other arm extending into the bore in the plate, 30 and means for retaining the hinge pin in position.

3. In a device of the class described the combination with a pair of hinge members having longitudinal bores extending along 35 their adjacent edges, one of the hinge members having a perforation extending through the wall of the bore, a U-shaped hinge pin having its arms extending into the bores in the members, a hook formed at the end of 40 one arm of the hinge pin and extending into a perforation in the one member, and a plug frictionally held in the bore at one end of one of the members for precluding displacement of the hinge pin.

In testimony whereof, I have hereunto subscribed my name this 21st day of March, 1925.

HUBERT AUBURN.
